(57) **CLAIM**

What is claimed is the ornamental design for a channel for a golf club head, as shown and described.

DESCRIPTION

FIG. 1 is a top front perspective view of a channel for a golf club head showing the new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear side elevational view thereof; and,

FIG. 7 is a front side elevational view thereof.

Any elements shown in dotted and/or dashed lines are provided for illustrative purposes only and form no part of the design claimed. Any surface shading is used solely to show the character or contour of the surfaces represented.
